(57) **CLAIM**

The ornamental design for a cylindrical deduster, as shown and described.

DESCRIPTION

FIG. 1 is a front perspective view of a first embodiment of the cylindrical deduster, the cylindrical housing having a circular discharge member mounted on an upper transparent cylindrical housing member, which is mounted on an opaque lower cylindrical housing member, the air inlet conduit being associated with the lower housing member and the air discharge conduit being associated with the circular discharge member, the circular dedusting apparatus being shown in phantom lines as being visible through the transparent upper housing member depicts unclaimed environmental subject matter and forms no part of the claimed design;

FIG. 2 is a front elevational view thereof, the cylindrical deduster being shown in phantom lines as being visible through the transparent upper housing member depicts unclaimed environmental subject matter and forms no part of the claimed design;

FIG. 3 is a rear elevational view thereof;

FIG. 4 is a right side elevational view thereof;

FIG. 5 is a left side elevational view thereof;

FIG. 6 is a top plan view thereof, with the conical infeed structure directing particulate material to the dedusting apparatus being shown in phantom lines depicting unclaimed environmental subject matter and forming no part of the claimed design;

FIG. 7 is a bottom plan view of the cylindrical deduster housing with the air infeed conduit leading into the bottom of the circular wash deck portion showing through the material discharge opening in the bottom surface of the housing shown in phantom lines depicting unclaimed environmental subject matter and forming no part of the claimed design;

FIG. 8 is a front perspective view of a second embodiment of the cylindrical deduster, the cylindrical housing having a circular discharge member mounted on an opaque cylindrical housing member, the air inlet conduit being associated with the housing member and the air discharge conduit being associated with the circular discharge member;

FIG. 9 is a front elevational view thereof;

FIG. 10 is a rear elevational view thereof;

FIG. 11 is a right side elevational view thereof; and,

FIG. 12 is a left side elevational view thereof.
